UNITED STATES PATENT OFFICE.

EMMETT MILLS HOWARD, OF HIGH POINT, NORTH CAROLINA, ASSIGNOR TO EJECT-O-FILE COMPANY, OF HIGH POINT, NORTH CAROLINA, A CORPORATION OF NORTH CAROLINA.

TALKING-MACHINE.

1,334,374.

Specification of Letters Patent. Patented Mar. 23, 1920.

Application filed April 24, 1919. Serial No. 292,271.

To all whom it may concern:

Be it known that I, EMMETT M. HOWARD, a citizen of the United States, residing at High Point, Guilford county, State of North Carolina, have invented a new and useful Talking-Machine, of which the following is a specification.

In the manufacture of phonographs or talking machines of the types commonly in vogue or upon the market, it has heretofore generally been the practice to attach the rear or enlarged end of the tone arm to a relatively fixed or immovable plate or board within the top of the talking machine cabinet, the motor being in some instances attached to the bottom of the motor board or partition, the latter being generally secured in position by screws so that it necessitates unscrewing said screws in said partitioning board, which carries the motor before the latter and its adjuncts are accessible, it being also generally necessary to swing the tone arm to one side into its extreme position, before attempting to lift or remove the motor board or to get access to said motor.

This procedure takes some little time and the interior of the talking machine and the motor is therefore practically inaccessible, particularly, when it is desired to oil the motor or to obtain access to the upper interior portion of the talking machine cabinet in order to enable a salesman to explain the internal construction thereof.

All the foregoing objections are obviated by my present invention, wherein I provide an upper, bottom, partitioning tray, the bottom of said tray having the talking machine motor secured thereto, while the upper rear portion of said tray has the base or coupling of the tone arm secured thereto, said partition board, or tray, being if desired, hinged to the front of the cabinet, so that the tray, motor, spindle, turn table and tone arm can be lifted or tilted upwardly, as a unit, whereupon the motor is readily accessible to an inexperienced person for oiling or inspection and the construction of the horn and the connection intermediate the tone arm and horn can be readily seen and the construction explained by a salesman to a prospective customer.

My invention further consists of a novel construction of a tray comprising a horizontal bottom partition, a vertical front and

side walls and an inclined rear wall, which latter is adapted to abut against the rear of the cabinet, said front vertical wall of the tray being if desired hinged or otherwise secured interiorly to the front of the cabinet, so that said tray, motor, spindle, turn table and tone arm can be lifted or tilted upwardly in unison as a unit, when desired.

To the above ends, my invention consists of a novel construction of talking machine and its adjuncts, as will be hereinafter fully set forth.

For the purpose of illustrating my invention, I have shown in the accompanying drawings embodiments which are at present preferred by me, since the same in practice will be found to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of a phonograph or talking machine embodying my invention, showing the top of the tray and its adjuncts.

Fig. 2 represents a perspective view of the tray in detached position with the motor, tone arm and their adjuncts removed therefrom.

Fig. 3 represents a section on line 3—3' of Fig. 1.

Fig. 4 represents a sectional view similar to Fig. 3 but showing the tray, motor, motor spindle, turn table, tone arm and their adjuncts in tilted position for the purpose of enabling access to the interior.

Fig. 5 represents a perspective view of the horn supporting cradle in detached position.

Similar numerals of reference indicate corresponding parts.

Referring to the drawings,

1 designates a talking machine cabinet to the upper portion of which is hinged or otherwise movably secured by novel construction of bottom partitioning tray 2 and its adjuncts, said tray comprising the bottom or partitioning member or motor board 3 to the under side of which is attached the motor 4 of any suitable construction, said motor having the spindle 5 which projects through the hole 6 in said bottom 3 and car-

100

110

ries the turn table 7 on which a record 8 of the usual character is rotated or played. The front wall 9 of the tray is vertical or extends at a right-angle to the bottom 3. 5 The sides 10 are also vertical with respect to the bottom while the rear wall of the tray is preferably inclined, the upper portion 12 thereof abutting against the upper internal rear wall of the cabinet. The vertical front wall 9 of the tray may be supported by the hinges 13 having the screws 14 entering the upper front wall 15 of the cabinet, one or two hinges being employed, or screws 34 passing through the sides 10 10 may be employed.

16 designates a tone arm of any suitable or conventional type, the same having a coupling 18 of the usual character, which is secured to the bottom 3 of the tray by suitable fastening devices as 19, said coupling 18 alining with a hole 20 extending through the bottom of the tray at its rear, said hole alining with the inlet opening 21 of the concealed horn 22, said horn and its inlet opening 25 being positioned with respect to the tone arm 16 if desired by means of the depending sleeve 23 or its equivalent secured to said bottom which may be employed if desired.

The horn 22 is disconnected from the 30 sides, bottom or other portion of the cabinet being preferably supported above the partition 24 or the like by means of a transverse bar 35 or screws 36 or a cradle 25 or its equivalent, the upper end of said cradle being secured to or supporting the horn body in any suitable manner and the base of said cradle 25 resting upon or being secured to said partition 24, the sounds produced being discharged through a suitable 40 grating 26 in the front of the cabinet 1. In addition to the holes 6 for the spindle 5 and the hole 20 alining with the tone arm which extend through the base or bottom 3 of the tray, I provide the additional small holes 27, 28 and 29 for the reception of the 45 needle cups.

The cabinet may be provided with a top or cover of any usual or conventional type. The parts normally appear as seen in Figs. 50 1 and 3, the position of the tray and its adjuncts being assured with respect to the horn 22 by reason of the contact of the vertical walls 9 and 10 with the front and sides of the upper portion of the cabinet body, whereby the tray is at once positioned, when it is dropped in place, it being apparent that the rear inclined wall 11 readily assumes its proper position with respect to the rear wall of the top of the cabinet when the tray is 55 down or in its normal position, the weight of the tray and its adjuncts causing them to settle down into their proper position, so that a record can be readily played, as is evident. When it is desired for any reason 60 to obtain access to the interior of the top of

the cabinet to inspect or oil the motor or to explain the internal construction for selling, demonstrating or other purposes, it is only necessary to remove the screws 34 lift the tray 2 upon its hinges into the position seen 70 in Fig. 4, whereupon the tray, motor, spindle, turn table and tone arm are lifted or tilted as a unit, the tone arm being prevented from swinging by any suitable support or locking device not shown, if desired. 75

When the tray and its adjuncts are elevated or tilted into the position shown in Fig. 4, it will be evident that the motor can be readily inspected for the purposes of oiling or repair and it will be further apparent 80 that by my novel construction the interior of the top of the cabinet is readily accessible. When the tray 2 is in its normal or lowest position it is held accurately in fixed position by the hinges or screws 34 and the 85 contact of the vertical front and side walls with the contiguous portions of the talking machine cabinet. By the provision of the rear inclined wall 11 the tray and its adjuncts can be readily lifted into the position 90 seen in Fig. 4.

My invention facilitates and reduces the cost of manufacture for the reason that the trays 2 can be made in quantities and the motor and its adjuncts and the tone arm and 95 its adjuncts readily secured thereto, whereupon said tray, tone arm, motor and their adjuncts can be handled, shipped or assembled as a unit, thereby enabling the wood-work or cabinet work in connection with the apparatus, comprising the cabinet body 1 and horn 22 to be manufactured at a different point from the tray and its adjuncts, if desired, so that these parts can be shipped 100 to a common destination and there assembled thereby reducing the cost of manufacturing and assembling devices of this character.

So far as I am aware, I am the first in the art to provide an upper, bottom partitioning device, plate or tray of this character wherein said motor and its adjuncts and the tone arm and its adjuncts are secured thereto, so that these elements can be lifted, 110 shipped, transported or handled as a unit, and my claims to these features are to be interpreted with the scope accorded to inventions of this character.

I have deemed it unnecessary to describe in detail the construction of the motor or the precise manner of securing the same in 115 position, as any conventional type of motor can be employed and the same can be secured to the bottom of the partitioning member 3 in any desired manner.

I have also deemed it unnecessary to describe in detail the manner of mounting and securing the horn 22 in position, it being understood that in accordance with my invention said horn may be mounted in the cabinet 1 on the bar 35 so as to permit ex- 125 130

traneous vibration thereof, the trough-shaped portion of the cradle 25 being lined with felt if desired. I may, however, mount my concealed horn rigidly or removably 5 within the cabinet, if desired, since this is a common right and open to the public and is public property and I, therefore, do not desire to be limited to any specific means 10 for securing my concealed horn in position. If desired, the sleeve 23 can be omitted and in lieu thereof a flat gasket or annular ring of rubber, leather, metal or other suitable material employed. Any conventional type of tone arm may be employed 15 but I preferably use one with an adjustable sound box adapted for the playing of hill and dale or laterally undulating grooved records. If desired, I may employ a valve 32 in the horn 22 for regulating the volume 20 of the sound and I may also equip the lower portion of the cabinet with record holding compartments having the partitions 30 and ejector levers 31 therefor. I may also provide the bottom of the horn 22 with the 25 stops 33 to prevent the horn from shifting with respect to the cradle 25.

It will now be apparent that I have devised a novel and useful construction of a talking machine which embodies the features of advantage enumerated as desirable 30 in the statement of the invention and the above description, and while I have, in the present instance, shown and described preferred embodiments thereof which will give 35 in practice satisfactory and reliable results, it is to be understood that the same are sus-

ceptible of modification in various particulars without departing from the spirit or scope of the invention or sacrificing any of its advantages.

Having thus described my invention, what I claim as new and desire to secure by Letters Patent, is:—

1. The combination of a talking machine cabinet having an upper open end, and a tray secured therein having vertical front and side walls, a rear wall and a bottom, the latter having front and rear holes therein for a motor spindle and tone arm, said walls being adapted to fit within and coat with the upper portion of said cabinet to position said tray therein.

2. The combination of a talking machine cabinet having an upper open end, and a tray secured therein and provided with vertical front and side walls, an inclined rear wall and a bottom, the latter having front and rear holes therein, for a motor spindle and tone arm, said inclined rear wall serving to position said tray when assembled, within the top of said cabinet.

3. As an improved article of manufacture, a tray for a talking machine cabinet adapted to fit the upper portion thereof, and having front and side vertical walls, an inclined rear wall, and a bottom having front and rear holes therein for a motor spindle and tone arm.

EMMETT MILLS HOWARD.
